Primary Examiner — Kelley A Donnelly*(74) Attorney, Agent, or Firm* — Tommy S F Wang;
Wang IP Law Group, P.C.(57) **CLAIM**

The ornamental design for a sliding shelf as shown and described.

DESCRIPTION

FIG. 1 is a rear perspective view of a sliding shelf showing my new design;

FIG. 2 is a front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another rear perspective view showing a shelf being pulled out;

FIG. 10 is an enlarged view of an indicated portion of FIG. 1; and,

FIG. 11 is an enlarged view of an indicated portion of FIG. 1.

The broken line portions of the sliding shelf in FIGS. 1–11 represent unclaimed portions of the claimed design and form no part thereof. The dot-dash broken lines in FIGS. 1–2 and 5–11 represent unclaimed boundary lines and form no part of the claimed design.
